UNITED STATES PATENT OFFICE.

HARRIS B. HOLT, OF DORMONT, PENNSYLVANIA, ASSIGNOR TO ROSEDALE FOUNDRY & MACHINE COMPANY, OF PITTSBURGH, PENNSYLVANIA, A CORPORATION OF PENNSYLVANIA.

FURNACE GRATE.

Application filed March 23, 1923. Serial No. 627,045.

To all whom it may concern:

Be it known that I, HARRIS B. HOLT, residing at Dormont, in the county of Allegheny and State of Pennsylvania, a citizen of the United States, have invented or discovered certain new and useful Improvements in Furnace Grates, of which improvements the following is a specification.

My invention relates to furnace grates, and particularly to endless-chain grates, and consists specifically of a grate link which may be inserted by way of replacement in an assembled grate structure, without the necessity of taking the structure apart.

In an application for Letters Patent of the United States filed by me July 14, 1922, Serial No. 575,059, I have described a grate structure, and to such a structure as that my present invention is applicable.

In the accompanying drawings Fig. I is a fragmentary view in plan from above of a grate structure in which my invention is present; Fig. II is a view in longitudinal section, on the plane indicated by the line II-II, Fig. I; Figs. III and IV are views to larger scale, showing in side and front elevation one of the link halves, in which my present invention centers.

The grate is made up of links pivoted together and grate bars borne by the links. The links are indicated in the drawings by the numeral 1, and the pins pivoting them together by 2. The grate bars are indicated by the numeral 3. The links are elongate bodies of cast iron, provided at their ends with transverse holes for the pivot pins. The multitude of links is assembled and is by the pivot pins articulated to constitute an endless chain belt. The arrangement in this respect is a familiar one, and will on brief examination of the drawings be recognized. The links are arranged in transverse rows; they stand apart at intervals equal to the thickness of a link; the ends of the links of adjacent rows are interlocked; and the pivot pins unite them, row with row, through the so interlocked ends. Thus the successive rows of links stand in echelon formation, while the whole articulated assembly forms an endless flexible belt, with openings or meshes between the links. This open-work character of the structure permits passage of air in sufficient quantities to nourish combustion of fuel resting on the grate bars

above. The endless belt so constituted will be understood to be carried on opposite sprocket wheels, as is usual.

Each link is provided on one side with an outstanding essentially T-shaped lug 13. 60 This lug is substantially twice as wide as is the body of the link from which it extends. When assembly is made of the links these aligned lugs of adjacent links form substantially continuous T-shaped rails extending 65 across the belt from side to side. And every row of links carries such a compound rail.

The grate bars 3 are (excepting only the marginal bars, which need not here be considered) identical. They are essentially fuel-supporting plates, ordinarily iron castings, each provided underneath with two transversely extending convergent lugs 31, which define and form an opening, by which 70 the grate bars may be strung upon and retained upon the T-shaped rails of the chain structure. The grate bars are strung one after another upon the rails, after the links themselves have, in the manner already described, been assembled. The grate bars when applied stand in close succession and the rows succeed one another closely. They are so formed that when assembled they 75 overlap, in testudo formation, both transversely and longitudinally of the structure.

All these matters are fully explained in my earlier application, mentioned above, and do not require further explanation here.

I now direct attention to the lower middle link of the chain, as shown in Figs. I and II. It is divided on a transverse medial vertical plane into two duplicate half links 17 oppositely set. These link halves are further modified, in that the openings for the pivot pins 2, instead of being closed eyes, are approximately semi-cylindrical,—in fact, a little more than half cylinders in their extent. The break in the continuity (a, Fig. 100 IV) is so arranged that, when the link half stands in the vertical position shown in Figs. II and IV, the edges of the break extend beyond the vertical plane through the axis of pivot, both above and below. 105 The break however is sufficiently wide to admit passage of the pivot pin laterally through it. Finally the link half at its lower inner corner is truncated, as at b, Fig. IV, so that the two link halves may be ap- 110

plied by rotary movement around the pivotal center. The surfaces *c*, however, abut, when the link halves are assembled, and when they are so assembled, and a grate bar 3 applied, the structure is locked against separation, except by removal again of the grate bar.

The assembly is sufficiently indicated in Fig. II. Two link halves are applied to 10 adjacent pins 2 and brought to position, back to back. This is accomplished, as has been indicated, by rotary movement of one or both link halves in bringing them to place. When they are brought to position 15 back to back, their lateral extensions form part of the continuous T-shaped bar which extends across the assembled belt. The grate bars are strung on, and these bars, or such one or more of them as overlie 20 the link of modified structure, lock its halves, so that the pair serve as though they were an integral piece.

The grate may be built up, using chiefly such link halves, with only a sufficient number of the links 1 with complete eyes 12 to keep adjacent pivot pins 2 from separating and hold the whole integrated. Primarily I intend using these link halves as repair parts. If a link breaks, it is not 25 necessary to take the whole apart in order to make repair; it suffices to remove the grate bars, crack away with a hammer the pieces of the broken link, and then to replace the link so broken and removed with 30 a pair of the repair parts of my invention. The grate bars may then be replaced and 35 the grate is again in good condition.

I claim as my invention:

1. In a chain grate the combination with a plurality of links and pivot rods connected thereby, said links being surmounted by fuel supporting members, of a sectional structure between two of said pivot rods said structure consisting of two symmetrically formed parts, each of which is formed with a recess adapted to engage one of said rods and said parts, when in operative position, cooperating to form a T-shaped, laterally extending lug, adapted for engagement with a fuel supporting member, and a fuel supporting member engaged therewith, and serving to lock said parts in operative position.

2. A replacement member for a chain grate which includes in its structure links, pivot rods, and fuel-supporting members, said replacement member adapted to form with a companion piece a replacement part for a grate link, said member being provided at one end with a recess adapted to engage a pivot rod of the grate structure, and at the opposite end presenting a square surface for abutment upon a companion piece, and being provided further intermediate its ends with a projection adapted to form with a corresponding projection upon the companion piece a lug for engagement by a fuel-supporting member of the grate.

In testimony whereof I have hereunto set my hand.

HARRIS B. HOLT.
